UNITED STATES PATENT OFFICE.

BENJAMIN F. GILMER, OF DENISON, TEXAS.

ROCKING-CHAIR FAN.

SPECIFICATION forming part of Letters Patent No. 766,822, dated August 9, 1904.

Application filed December 18, 1903. Serial No. 185,747. (No model.)

To all whom it may concern:

Be it known that I, BENJAMIN F. GILMER, a citizen of the United States, residing at Denison, in the county of Grayson and State of 5 Texas, have invented a new and useful Rocking-Chair Fan, of which the following is a specification.

This invention relates to attachments to 10 rocking-chairs whereby a fan may be caused to vibrate by the motion of the chair, and has for its object to simplify and improve the construction and provide means whereby the improved device may be detachably connected to any form of rocking-chair or similar structure and without injury to the chair; and the 15 invention consists in certain novel features of construction, as hereinafter shown and described, and specified in the claims.

In the drawings illustrative of the invention, 20 in which corresponding parts are denoted by like designating characters, Figure 1 is a side view of a rocking-chair with the improved attachment applied. Fig. 2 is a front view of the device detached.

The improved device may be attached to any 25 of the various forms of rocking-chairs, and consists of a base or supporting member 10, clamped, as at 11, to the rocking-chair 12, preferably near its forward part, and having 30 a guide 13 extending laterally therefrom, as shown. Supported slidably in the guide is a standard 14, resting by its lower end at 15 upon the floor 16 and provided at its upper end with a yoke 17 18. Mounted for rotation 35 in the yoke is a shaft 19, carrying a fan of any approved form, but preferably composed of spaced blades or wings 20, as shown. Connected by one end to the standard 14 is a retracting-spring 21, and leading from the 40 other end of the spring is a cord or flexible wire 22, which is wound several times around the shaft 19 and connected at its other end in this instance to an eye 10^x, carried by the supporting member 10. The lower end 15 of the standard 14 will be provided with means, such as a soft-rubber or similar shoe or a spur, to cause it to adhere to the floor with sufficient firmness to prevent slipping when the chair is rocked. By this simple arrangement 45 it will be obvious that when the chair 12

is rocked forward and backward the guide 13 will move upwardly and downwardly upon the standard 14 and cause the latter to vibrate to and fro upon its lower end as a center, while at the same time the flexible member 22 55 will be carried downward with the forward portion of the chair at the forward movement, and thus rotate the shaft and correspondingly rotate the fan and at the same time incidentally expand the spring 21, and at the return stroke 60 the reaction of the spring in taking up the slack of the flexible member will rotate the fan in the opposite direction, as will be obvious. Thus the fan will be rotated and moved bodily forward and backward with the motion of the chair.

The members 10 and 14 will preferably be of wood of the same quality and finish as the frame of the chair to correspond therewith, and the guide 13 may be merely a screw-eye 70 inserted into the member 10, while the shaft 19 and fan-arms may be of metal plated or otherwise ornamented and the fan-blades of cloth stretched over frames attached to the fan-arms, as shown, whereby strength and lightness will 75 be combined.

The fan-blades and other parts may be ornamented in any desired fanciful manner.

It will be noted that a very simple, cheaply-constructed, and easily applied and operated 80 device is produced which may be readily applied to any style or form of rocking-chair and that the parts may be modified in minor particulars without departing from the principle of the invention or sacrificing any of its 85 advantages.

Having thus described the invention, what is claimed is—

1. The combination with a rocking-chair having a lateral guide, of a fan attachment 90 comprising a standard slidably supported in said guide and resting upon the floor, a shaft mounted for rotation upon said standard and carrying a fan, a retractive spring, and a flexible member connected at its ends to said spring 95 and to a fixed part of the chair and intermediate wound around said shaft, whereby the rocking motion of said chair will cause said fan-shaft and fan to be rotated.

2. The combination with a rocking-chair, of 100

a fan attachment therefor comprising an arm for detachable connection to the chair and having a lateral guide, a standard slidably supported by said guide and resting upon the floor, 5 a shaft mounted for rotation in the upper end of the standard and carrying a fan, and a flexible member connected at one end to a fixed part of the chair, and at its other end to a retractive spring wound around said shaft, whereby the 10 rocking motion of said chair will cause said fan-shaft and fan to be rotated.

3. The combination with a rocking-chair having a lateral guide, of a fan attachment comprising a standard slidably supported in

said guide and provided at its upper end with 15 a yoke, a shaft mounted for rotation in the yoke and carrying a fan upon its extended end, a reTRACTING-SPRING secured at one end within the yoke, and a flexible member wound around said shaft and connected at one end to the spring and 20 at its other end to a fixed part of the chair.

In testimony that I claim the foregoing as my own I have hereto affixed my signature in the presence of two witnesses.

B. F. GILMER.
